JOHN E. ANDERSON, OF CHICAGO, ILLINOIS, ASSIGNOR TO PLIBRICO JOINTLESS FIRE-
BRICK COMPANY, OF CHICAGO, ILLINOIS, A CORPORATION OF ILLINOIS

FURNACE CONSTRUCTION

Application filed June 12, 1930. Serial No. 460,599.

This invention relates to furnace linings and, more particularly, to corbel locking tiles adapted to secure or anchor refractory linings to the structural walls of furnace or like constructions.

Attempts have been made by fire brick manufacturers to provide tiles for sectionally supporting refractory linings, but thus far none has been developed which also incorporates a locking device. The problem which manufacturers of plastic or fire brick linings have to solve is that of preventing the lining from bulging and breaking away from the structural supporting wall. Several factors are present which cause this objectionable tendency, chief among them being the weight of the lining and the extreme heat and consequent expansion and contraction. In some boiler installations, the refractory lining extends vertically for twenty feet or more, and the weight of the lining, with its consequent buckling stresses, tends to force the lining away from the supporting wall. This is especially true in installations where a monolithic lining is used. The lining is subjected to the heat of the furnace and expands and contracts to a greater extent and at a different rate than the supporting wall of the furnace. This results in rapid deterioration and bulging of the lining away from the supporting wall, with consequent cracking and destruction of the lining, unless means is provided for supporting the lining in such manner as to hold it to the furnace wall while permitting it to expand and contract independently of such wall. One of the main objects of my invention is to provide a novel locking tile whereby the lining is supported and secured in such manner as to permit independent expansion and contraction thereof. This tile is of such dimensions as to be firmly embedded in the structural brick wall of the furnace, and is provided with a locking element adapted to hold the lining against movement away from the wall. The tiles may be so arranged as to support the lining in sections held in place by the tiles. This construction allows a lining of relatively great vertical height to be constructed which will not have objectionable buckling stresses, the weight of

the lining being transferred to the structural brick wall at convenient sectional supporting points.

The locking element of the tile is placed so as to anchor the lining to the wall; the tile being so imbedded that no lateral movement of it with respect to the wall is possible. This effectually holds the lining to the wall thru the locking tile.

In the drawings:—

Figure 1 is a fragmentary inner face view of a furnace lining, as applied in accordance with my invention;

Figure 2 is a sectional view taken substantially on line 2—2 of Figure 1;

Figure 3 is a view similar to Figure 1, but showing my invention as applied to a continuous monolithic wall, which is sectionally supported by the tile of my invention;

Figure 4 is a sectional view taken substantially on line 4—4 of Figure 3;

Figure 5 is a perspective view of the locking tile.

Referring to the embodiment shown in Figures 1 and 2, reference numeral 6 designates an outer structural brick wall of a furnace, which wall is used for supporting purposes only. On the inner face of this wall is disposed a refractory lining, consisting of a fire brick lining 7 above the lowest tube line of the boiler, and a monolithic lining 8 disposed below said tube line. The tube line of the boiler is indicated (Figure 1) by the slant of the tube 9, which is the lowermost boiler tube. In such constructions, the service required of the refractory lining is not as severe above the tube line as below such line, and, therefore, fire bricks may be used above this line.

Separating the polylithic fire brick lining 7 from the monolithic lining 8 are the corbel locking tiles 10, as shown, formed of refractory material. A small clearance space 10' exists between the lower surface of the tile and the upper surface of the lining due to the natural contraction of the lining after it dries and hardens. This space allows the expansion of the lining due to the heat within the furnace, without imposing any stresses upon

the lining that would tend to cause buckling thereof.

Each tile comprises a body 19 of rectangular shape in cross-section and a head element 15 projecting from one side of the body perpendicular thereto. Element 15 extends over a reduced portion or tongue 8a of lining 8 with surface 16 adjacent the outer face of the tongue. This provides a tongue and groove connection between the tiles and the lining. The tiles serve as a support for the upper fire brick lining 7, and as an anchor and lock for the lining 8. The major portion of the tile is imbedded in wall 6 and transmits the weight of the refractory brick lining to this wall. The lower lining is held in position by means of the locking element of the tile, and also by means of a flexible anchor 11, of the type shown and described in the co-pending application of Ivon S. Pieters, Serial No. 123,825, filed July 21, 1926. This type of anchor consists of two members, one firmly embedded in the structural wall, and having a projecting portion engaging a slot in the other member, which is embedded in the lining, in a manner which permits vertical and lateral movement of the lining member, but holds it against movement away from the wall.

In constructions where the lining is a monolithic lining of rather considerable height, as in some boiler installations where the lining extends vertically for twenty feet or more, the weight of the lining itself is liable to cause buckling, and resultant breaking away and spalling of the wall. To prevent this, I have provided a novel means for both supporting the weight of the lining and also anchoring it to the structural wall by means of my locking tile. A construction of this type is shown in Figures 3 and 4.

This construction permits the wall to be separated into sections and supported at these sectional points by the corbel type of tile which transmits the weight of the lining to the brick wall.

In the drawings, 12 represents a plastic monolithic lining set against a structural brick wall 6. Sectionally dividing and supporting the lining is a row of corbel locking tiles 10 firmly embedded in the wall 6. As will be noted, the tiles are disposed with their locking elements projecting alternately upwardly and downwardly, so that they not only support the lining, but also serve to anchor the lining against movement away from the wall 6. An angle buckstay is shown at 13, suitably secured to the wall, as by means of an angle strip 13a and tie rods 13b. Flexible anchors, as previously mentioned, are shown at 11. By the novel method of placing the tiles in alternating relation, it is possible to anchor both sections of the lining, and also to transmit the weight of the sections thereof to the brick wall 6.

A perspective view of the tile is shown in Figure 5, and illustrates its form in detail. The tile 10 includes a major or body portion 14 which is adapted to project into and be firmly imbedded in the wall 6. At the other end of the tile, a projecting portion or head 15 of the tile forms an anchoring surface 16 which is adapted to contact with the lining and hold it against movement away from the wall.

Although primarily intended for anchoring refractory furnace linings, the invention is not to be limited solely to this type of anchorage, since other embodiments and adaptations might present themselves, and I intend to include all such variations, as fall within the scope of the appended claims, in this application, in which the preferred forms only of my invention are disclosed.

I claim:

1. In a furnace, a retaining wall, a polylithic lining, a monolithic lining, means for transmitting a major portion of the weight of said polylithic lining to said retaining wall, and means for holding said monolithic lining against movement away from the wall while permitting independent expansion and contraction thereof.

2. In a furnace, a retaining wall, a series of sections of monolithic lining, means comprising locking tiles having their major portions embedded in said retaining wall, said tiles separating and supporting said sections and holding them against movement away from said retaining wall.

3. In a furnace, a retaining wall, monolithic lining sections, and tiles projecting inwardly from the wall and having locking elements at their inner ends, the locking elements holding the lining sections against movement away from the wall while permitting expansion and contraction of said sections independently of the wall.

4. In a furnace, a supporting wall, a monolithic lining, and rigid supporting members secured to the wall and supporting the lining, said members having elements engaging about selected portions of said lining and holding the latter against movement away from the wall, there being clearance provided between said elements and the lining when said lining is cool, said clearance permitting expansion and contraction of the lining independently of the wall.

5. In a furnace, a supporting wall, a sectional monolithic lining, and securing means for engaging the respective lining sections at the upper and lower edges thereof, said means holding the lining against movement away from the wall and supporting the weight of the lining sections while permitting expansion and contraction thereof independently of said wall.

6. In a furnace, a supporting wall, a plurality of lining sections, securing means en-

gaging the respective lining sections at the upper and lower edges thereof and holding them against movement away from the wall while permitting expansion and contraction of said sections independently of the wall, and means anchoring the lining sections to the wall between said securing means and preventing movement of the lining away from the wall while permitting independent expansion and contraction thereof.

7. In a furnace, a supporting wall, a plurality of lining sections, securing means comprising rigid supporting members, said members having elements engaging about selected portions of said lining sections and holding said sections against movement away from said wall, said securing means supporting the weight of said lining sections while permitting expansion and contraction thereof independently of said wall.

8. In a furnace, a supporting wall, a plurality of lining sections, securing means comprising rigid supporting members, said members having elements engaging about selected portions of said lining sections and holding said sections against movement away from said wall, said securing means supporting the weight of said lining sections, there being clearance provided for permitting expansion and contraction of said sections independently of said wall.

9. In a furnace, a supporting wall, a plurality of lining sections, securing means for supporting said sections and having elements for engaging the upper and lower edges of respective sections to hold said sections against movement away from said wall, and means anchoring said sections to the wall and disposed between said securing means, said anchoring means preventing movement of said lining away from said wall while permitting expansion and contraction thereof independently of said wall, there being clearance provided between said lining sections and said securing means for permitting expansion and contraction of the lining sections independently of the wall.

10. In a furnace, a supporting wall, a plurality of lining sections, securing means for supporting said sections and having angularly disposed elements engaging the upper and lower edges of respective sections to hold said sections against movement away from said wall, and means anchoring said sections to the wall and disposed between said securing means, said anchoring means preventing movement of said lining away from said wall while permitting expansion and contraction thereof independently of said wall, there being clearance provided between said lining sections and said securing means for permitting expansion and contraction of the lining sections independently of the wall.

11. In a furnace, a supporting wall, a poly-

lithic lining being disposed above said monolithic lining and separated therefrom by rigid supporting members, said members serving to support said polylithic lining and being provided with elements engaging about selected portions of said monolithic lining and holding said monolithic lining against movement away from said wall while permitting independent expansion and contraction of the monolithic lining.

12. In a furnace, a supporting wall, a polylithic lining, a monolithic lining, said polylithic lining being disposed above said monolithic lining and separated therefrom by rigid supporting members, said members serving to support said polylithic lining and being provided with elements engaging about selected portions of said monolithic lining and holding said monolithic lining against movement away from said wall, there being clearance provided between said members and the monolithic lining permitting independent expansion and contraction of said lining.

13. In a furnace, a supporting wall, a polylithic lining, a monolithic lining, said polylithic lining being disposed above said monolithic lining, rigid members supporting the polylithic lining, and means anchoring said monolithic lining to the wall and disposed below said members and permitting expansion and contraction of the monolithic lining independently of the wall while preventing movement thereof away from said wall, said members having elements disposed to engage about selected portions of said monolithic lining to hold said lining against movement away from said wall while permitting independent expansion and contraction thereof.

14. In a furnace, a supporting wall, a polylithic lining, a monolithic lining, said polylithic lining being disposed above said monolithic lining, rigid members supporting the polylithic lining, and means anchoring said monolithic lining to the wall and disposed below said members and permitting expansion and contraction of the monolithic lining independently of the wall while preventing movement thereof away from said wall, said members having elements disposed to engage about selected portions of said monolithic lining to hold said lining against movement away from said wall, there being clearance provided between said members and the monolithic lining permitting independent vertical expansion and contraction thereof.

15. In a furnace construction, a retaining wall, a refractory lining at the inner face of the wall, and rigid supporting members secured to the wall and projecting inwardly therefrom, said members having elements engaging over selected portions of the lining and holding it against movement away from the wall, there being clearance between certain of the supporting members and the lin-

ing and such clearance permitting expansion and contraction of the lining independently of the wall.

16. In a furnace construction, a retaining wall, a sectional refractory lining at the inner face of the wall, and rigid supporting members secured to the wall and extending between the upper and lower edges of the lining sections, said members having elements engaging over the edge portions of the lining sections and holding them against movement away from the wall, there being clearance between the upper edges of the respective lining sections and the associated supporting members for permitting expansion and contraction of the lining sections independently of the wall.

17. In a furnace construction, a retaining wall, a sectional refractory lining at the inner face of the wall, and rigid supporting members secured to the wall and extending between the upper and lower edges of the lining sections, said members having tongue and groove connections with the lining sections and holding them against movement away from the wall, there being clearance between certain of the supporting members and the associated edges of the respective lining sections for permitting expansion and contraction of the lining sections independently of the wall.

In witness whereof, I hereunto subscribe my name this 7th day of June, 1930.

JOHN E. ANDERSON.
